UNITED STATES PATENT OFFICE.

EDWIN GOULD OVER, OF FORT WORTH, TEXAS.

SANITARY TOOTH-CLEANER.

1,144,777.

Specification of Letters Patent. Patented June 29, 1915.

Application filed September 22, 1914. Serial No. 863,004.

To all whom it may concern:

Be it known that I, EDWIN G. OVER, a citizen of the United States, and a resident of Fort Worth, in the county of Tarrant and State of Texas, have invented an Improvement in Sanitary Tooth-Cleaners, of which the following is a specification.

The object of the invention is to provide an inexpensive, effective, and sanitary device adapted to serve as a substitute for a brush in cleaning the teeth.

The device comprises two pockets, the partition between which is extended. One pocket is formed of thin, close-mesh fabric adapted to receive the index finger, and the outer side of the other pocket is formed of an open-mesh fabric through which tooth-powder readily passes. The extension of the partition beyond the pockets serves as a pull-piece and also for clamping upon the finger when the device is being used.

The details of construction, arrangement, and combination of parts are hereinafter described, and illustrated in the accompanying drawings, in which—

Figure 1 is a view representing the device as applied to the index finger and clamped thereon as when in use. Fig. 2 is a plan view of the device with the close-mesh fabric forming the face. Fig. 3 is a plan view of the opposite side of the device. Fig. 4 is an enlarged longitudinal section of the device, powder being shown contained in the pocket having the open-mesh face. Fig. 5 is a cross section on the line 5—5 of Fig. 4.

In Figs. 4 and 5, 1 indicates the finger pocket and 2 the powder pocket; 3 indicates the partition between the pockets, and 3^a the extended portion of the same which serves as a pull- and clamp-piece as hereinafter described. The outer or face side of the finger pocket and also the partition 3 are made of close-mesh fabric through which tooth powder cannot pass, while the face or outer side

of the powder pocket is made of coarse-mesh fabric through which tooth-powder may readily pass. A quantity of powder is shown in Fig. 4 contained in the pocket 2.

In using the device, a quantity of powder having been deposited in the pocket 2, the index finger is inserted in the pocket 1 and the device is drawn on to the finger by pulling the extension 3^a of the partition; then the extension 3^a being clamped by the thumb against the index finger as shown in Fig. 1, the side of the device having the coarse-mesh fabric is rubbed against the teeth, thus effectively cleaning them.

It will be understood that the loosely woven fabric constituting one face of the powder pocket may be made of cheese-cloth or gauze, and that the powder deposited in the pocket readily escapes when moistened and is thus rubbed on the teeth. The device is exceedingly convenient and effective for this purpose, and waste of tooth-powder is effectually prevented. The device is very inexpensive and entirely sanitary, because it is not intended to be used a second time.

I claim:—

The improved sanitary device, comprising two pockets arranged back to back, one formed of close-woven fabric which is impervious to tooth-powder, and the other having its face or outer side formed of relatively coarse-mesh fabric which is permeable to tooth-powder, the partition dividing the two pockets being also impervious to powder and extended a considerable distance beyond the mouths of the pockets, whereby it is adapted to serve as a pull-piece and for clamping and holding the device in place on the finger when being used, as described.

EDWIN GOULD OVER.
